D. 321,150 10/1991 Bulgari ..... D11/45*Primary Examiner*—Ralf Seifert*Attorney, Agent, or Firm*—Gottlieb, Rackman & Reisman, P.C.[57] **CLAIM**

The ornamental design for an earring, as shown and described.

DESCRIPTION

FIG. 1 is a front elevational view of an earring showing my new design;

FIG. 2 is a side elevational view;

FIG. 3 is left side elevational view;

FIG. 4 is a right side elevational view;

FIG. 5 is a top plan view; and,

FIG. 6 is a bottom plan view.

The broken line showing of an attachment element in FIGS. 1–6 is for illustrative purposes only and forms no part of the claimed design.
